UNITED STATES PATENT OFFICE.

WILLIAM E. McCARTY, OF RICHMOND, INDIANA.

DESIGN FOR A BADGE.

SPECIFICATION forming part of Design No. 32,378, dated March 27, 1900.

Application filed February 9, 1900. Serial No. 4,700. Term of patent 14 years.

To all whom it may concern:

Be it known that I, WILLIAM E. McCARTY, a citizen of the United States, residing at Richmond, in the county of Wayne and State of Indiana, have invented and produced a new and original Design for a Badge, of which the following is a specification, reference being had to the accompanying drawing, forming part thereof.

10 The figure shown in the drawing is a plan view fully showing my design.

The leading or material feature of my design consists of a badge having the shape, configuration, and ornamentation shown in 15 the drawing. On the upper wing of the Maltese cross is the representation of a dove. On the right-hand wing of the Maltese cross is

the representation of a Bible. On the lower wing of the Maltese cross is the representation of a lamb, and on the left wing of the Maltese cross is the representation of a flag.

Having described my invention, what I claim as new, and desire to secure by Letters Patent of the United States, is—

The design for a badge, as herein shown 25 and described.

In testimony whereof I have signed my name to this specification in the presence of two subscribing witnesses.

WILLIAM E. McCARTY.
